UNITED STATES PATENT OFFICE.

KATE MISSOURI DUFFEY, OF ASTORIA, OREGON.

BED-PAN.

SPECIFICATION forming part of Letters Patent No. 380,478, dated April 3, 1888.

Application filed June 22, 1887. Serial No. 242,148. (No model.)

To all whom it may concern.

Be it known that I, KATE MISSOURI DUFFEY, of Astoria, in the county of Clatsop and State of Oregon, have invented a new and Improved 5 Bed-Pan, of which the following is a full, clear, and exact description.

The object of the invention is to provide a bed-pan which can be used with but little inconvenience to the patient, can be easily 10 cleaned, and will prevent soiling of the bedding either by the patient in attending to the calls of nature or by the attendant in giving injections; and to these ends the invention consists in details of construction, as hereinafter 15 described and claimed.

Reference is to be had to the accompanying drawings, forming a part of this specification, in which similar letters of reference indicate corresponding parts in all the figures.

20 Figure 1 is a side elevation, the cap for closing the discharge pipe or neck being detached and in section. Fig. 2 is a longitudinal section on line *x x*, Fig. 3. Fig. 3 is a top view, and Fig. 4 is a cross-section on line *y y* of 25 Fig. 3.

The body *A* of the bed-pan is formed with the main opening *a*, the part of the said body surrounding the said opening at the rear thereof being raised, as at *b*, and gradually lowering 30 to the front of said opening, as at *c*. The rear raised end, *b*, terminates in the inwardly-projecting portion *d*, which forms the highest point of the pan and is adapted to project between the limbs of the patient, and thus effectually prevent soiling of the bedding when 35 the pan is being used. The extreme front end, *A'*, of the pan is made narrow and the upper surface at the narrowed end is concaved, as at *a'*, to form a better rest for that portion of the 40 patient's body resting thereon.

At the rear end, at the bottom, the pan is formed with the discharge neck or pipe *B*, which is externally-threaded to adapt it to receive an internally-threaded cap, *B'*, during 45 an evacuation by the patient, and which cap

may be removed and a hose, *C*, substituted therefor when the patient is receiving an injection or during the application of a medicinal wash, or when otherwise needful.

In practice the hose *C* will be arranged to 5c convey liquid contents of the pan to a vessel on the floor, and be provided with a clasp arranged to stop the flow of liquid through the pipe when desired. At the rear end, also, above the delivery-neck *B*, a handle, *D*, is 55 formed on the pan. By thus forming the handle in proximity to the liquid-discharge neck great convenience is afforded for arranging the pan, especially when the hose *C* is applied, and with but little inconvenience to the patient. In one side of the pan is formed a 60 spout, *E*, close to the body of the pan, by means of which spout the pan is easily emptied of faeces.

My improved bed-pan, besides possessing 65 the advantages set forth above, may be easily and thoroughly cleansed by reason of the neck *B* and spout *E*.

The cover *F* for the main opening *a* and the cover *G* for the spout *E* are made to conform 7c to the respective openings, and are for convenience connected together by a chain, *H*.

Having thus described my invention, what I claim as new, and desire to secure by Letters Patent, is—

1. The bed-pan *A*, formed with the main opening *a*, the rear portion of the pan being raised, as at *b*, the said raised portion terminating in a point, *d*, projecting into the main opening *a* in an upward and inward direction, 80 substantially as and for the purpose specified.

2. The bed-pan *A*, formed with the main opening *a*, the end discharge-neck, *B*, the handle *D* in proximity to said discharge-neck, and the spout *E* in one side of the pan, sub- 85 stantially as and for the purposes specified.

KATE MISSOURI DUFFEY.
